UNITED STATES PATENT OFFICE.

SAMUEL D. BUTTERWORTH, OF LANSING, MICHIGAN.

CONNECTING-DOOR LOCK.

Application filed February 18, 1922. Serial No. 537,372.

To all whom it may concern:

Be it known that I, SAMUEL D. BUTTERWORTH, a citizen of the United States, residing at Lansing, in the county of Ingham 5 and State of Michigan, have invented certain new and useful Improvements in Connecting-Door Locks, of which the following is a specification.

This invention relates to connecting door locks and has for its object a connecting door lock having a slideable bolt mechanism which does the work of the ordinary two lock bolts and the third latch member ordinarily utilized in connecting doors between adjoining 15 rooms. Furthermore, the customary turn knobs are entirely eliminated. Furthermore, the bolt mechanism is noiseless in its operation and the usual clicking of the latch is eliminated.

Another important feature is that the door is much more securely held than is ordinarily the case with the latch. Where a connecting door is not locked from either side the door must be held closed by the latch. It is a well known fact that latch strikers are not ordinarily placed with a great deal of skill by house carpenters and very often only the point of the latch reaches into the striker socket, and in fact, sometimes no part of the latch. This is sometimes due to the error of the carpenter or sometimes due to the shrinkage of the door. With one form of my invention when two lock bolts are employed and function as latch bolts, not only is a greater contact length of latch provided but when one of the latches possibly does not securely engage the striker the other may function successfully to accomplish this object. Hence the door will be held closed notwithstanding one of the bolts does not function as it should. These and other objects are accomplished by the structure which I shall now detail.

In the drawings,—

Fig. 1 is an elevation of the lock mechanism showing the striker in vertical cross section.

Fig. 2 is a section on the line 2—2 of Fig. 50 1, the upper thumb turn being turned through one-quarter of a turn.

Fig. 3 is a section on the line 3—3 of Fig. 1.

Fig. 4 is a detail of one of the shims used 55 in the adjustable striker.

Fig. 5 is a section on the line 5—5 of Fig. 1.

The lock housing is designated *a*. It is secured with the usual face plate *b* and has the front plate *d* and a cover plate *c*. This lock housing is a casting and is provided with a rib *e* which is provided with a suitable socket to afford a guide for the rear end portions of the sliding bolt rods *f* and *g*. Each of these bolt rods is provided with a yoke-like head *f'* and *g'*. The springs *h* coiled about these bolt rods have each one end abutting against the rib *e* and the other end engaging the bolt head. This tends to shoot the bolt head outward. The rubber washer *j* engaging at the rear of the rib arrests the outward movement of the bolt. The yoke-like heads each rotatably support the rubber rolls *k* which act as the striking surface of the bolt head.

These rolls permit the door to be opened simply by pulling upon it and it can be shut by slamming. An ordinary beveled bolt head cannot be opened except by retracting the bolt either by a lever or a turn knob. Hence this construction entirely eliminates the necessity of a turn knob or other retractor and the roll-back connections. These two bolts form a latch, when not dogged, and consequently do away with the necessity of the extra latch member ordinarily required in connecting doors. Furthermore, as explained in the introductory matter, they form a double latch construction which insures a latching engagement although one of the members is not functioning properly. Preferably the bolt mechanism is made in the form of two separate bolt heads and rollers, but, obviously, the bolt heads could be united to function as one.

These sliding bolts act as locks when they are deadlocked or dogged in a suitable manner. Ordinarily the lock for a connecting door requires two sliding bolts that have to be shot by means of two roll-backs and thumb-turns. With my construction no sliding bolt is required to be shot. When the door is shut the bolts are automatically shot into the striker socket by the springs. All that is required to make effective these combined latch bolts and lock bolts to function as lock bolts is to turn the thumb turn *m* which engages the locking dog *n* with the rear of the sliding bolt. A retaining spring *o* is used to engage either in one notch *y* 110

or in the other notch γ to hold the locking dog in one position or the other of its turning arc.

It is preferable to use pull handles r on both sides of the door. These pull handles may be manufactured with a suitable escutcheon g depending from the bottom of the pull handle in a suitable ornamental fashion and through this may pass and be rotatably supported the ornamental thumb turn m , making a very neat and attractive fixture.

What I claim is:

1. A connecting door lock, comprising a housing provided with a pair of sliding spring-pressed bolts having heads carrying rollers that engage in the striker socket, and locking dogs for separately dogging the two bolts, the said locking dogs operable from opposite sides of the door.

2. A connecting door lock, having in combination, a housing, a pair of sliding bolts, means for normally projecting said bolts, said bolts provided each with a head for rotatably supporting a roller arranged to engage in the socket of the striker, and a pair of thumb turns on opposite sides of the lock provided each with a dog which may be turned to dog one of the sliding bolts.

3. A connecting door lock having in combination, a housing, a rib supported by the housing, a pair of sliding bolts guided in the said ribs, a yoke-like bolt head carried by each bolt, a roller journaled by each bolt head for engaging in the socket of the striker, a pair of turn dogs located behind the end of each bolt and adapted to be turned into a position which holds the bolt from retraction, springs engaging each bolt head for normally projecting the same and turn-buttons on opposite sides of the door for engaging the dogs.

4. In a connecting door lock, the combination of a housing, a pair of sliding bolts provided with bolt heads having a contact

surface arranged to lie in the socket of the 45 striker and which may be disengaged from the striker by swinging the door, springs for normally keeping said bolt heads projected, separately-operating dogging members for dogging the bolt heads from movement to hold the bolt heads in engagement with the striker, and separate operating devices for the two dogs on opposite sides of the lock.

5. In a connecting door lock, the combination of a housing, a sliding bolt mechanism normally projected out of the housing and having one or more rolls for engaging in the striker socket, and separate dogs separately-operable from opposite sides of the 60 housing for engaging the sliding bolt mechanism whereby both dogs have to be released before the door can be opened.

6. In a connecting door lock, the combination of a housing, a sliding bolt mechanism yieldingly projected from the housing and provided with a striker contact surface arranged to engage in the striker socket and capable of being forced out of the striker socket by pushing or pulling on the door, 70 and separate dogging devices separately-operable from opposite sides of the door for dogging such bolt mechanism to prevent the door being opened until both the dogs are released.

7. In a connecting door lock, the combination of a housing, a sliding bolt mechanism including a pair of bolt rods and provided with a head construction having means to engage in the striker socket which can be 80 disengaged from the striker socket by simply pushing or pulling on the door, and separate turn dogs that can be turned to engage the ends of the bolt rods to dog the bolt, the two separate dogs being separately operable 85 from opposite sides of the door.

In testimony whereof I affix my signature
SAMUEL D. BUTTERWORTH
